**METHOD OF AND APPARATUS FOR BURNING
PARTICLE-FORM FUEL**

Arthur J. Gram, Jr., Limaville, and Warnie L. Sage, Louisville, Ohio, assignors to The Babcock & Wilcox Company, New York, N.Y., a corporation of New Jersey

Application September 7, 1954; Serial No. 454,358

8 Claims. (Cl. 110—28)

The present invention relates to a method of and apparatus for burning a particle-form combustible solid material which is characterized by a relatively low content of ash which is fusible under normal combustion conditions. More particularly, the invention relates to the burning of particle-form solid materials having both low combustible volatile and low ash contents.

Certain solid combustible materials occurring in nature or formed during manufacturing processes are characterized by low ash contents or when higher percentages of ash are present the ash is, at least partially, not fusible under ordinary furnace operating conditions. Frequently, such materials also have a low combustible volatile content, and a hardness making them difficult to pulverize. Examples of solid combustible materials having high fusion temperature ash may be found in certain woods, and coals where the material may have either a high or low volatile content, and may or may not be easy to grind. Solid materials having both a low ash and a low volatile content are exemplified by the coke residues obtained in the treatment of petroleum, more specifically, the residues known generally as "petroleum" or "pitch" coke, in which the ash content is of the order of 1.0% by weight of the coke and the volatile content is from 1.0 to 7.0% by weight. Such coke residues are usually extremely difficult to pulverize.

Attempts have been made to burn such low ash fuels in heat absorbing equipment, such as steam boilers, to recover their high heat values. Usually, the fuels in their available form are too coarse and too low in volatiles for burning in suspension without pulverization, which is necessarily expensive due to their low grindability. The fuels in their available form are, however, normally too fine for burning on a traveling grate because of excessive carry over of unburned material with resultant carbon loss and erosion of metal parts of the heat recovery equipment.

In accordance with the invention, particle-form solid materials of the character described can be successfully burned in a high temperature cyclonic type furnace chamber, the walls of which are maintained with a layer of viscous sticky refractory material thereon and onto which the coarser fuel particles are deposited by centrifugal force and burn in situ, while the finer fuel particles are burned in suspension. When the fuel is low in combustible volatile content, auxiliary fuel is supplied in sufficient quantity to insure maintenance of furnace temperatures above the ignition temperature of the coke and above the fusion temperature of the furnace wall coating material. The wall coating material is formed by utilizing as the auxiliary fuel either a particle-form high volatile bituminous coal having a relatively low ash fusion temperature (e.g. 2000-2400° F.) and at least a medium ash content, or fuel oil or gas in conjunction with an intermittent or continuous supply of a refractory slag-forming material having a fusion temperature below the normal mean furnace chamber temperature. In the latter case and also where the amount of coal ash available is insuffi-

cient to supply the required amount of wall coating material, the molten slag discharged from the cyclone furnace is reduced to a relatively finely divided or granulated condition by quenching in water or by rapid cooling, and recycled to the cyclone furnace chamber.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which a preferred embodiment of the invention has been illustrated and described.

Of the drawings:

Fig. 1 is a partly diagrammatic elevation of an installation incorporating the present invention; and

Fig. 2 is a vertical section taken on the line 2—2 of Fig. 1.

In the drawings, the invention is illustrated as applied to the combustion of a particle-form petroleum coke which is the residue of a petroleum refining process of the fluidized bed type, where the residue is known as "fluidized coke," having a heat value of approximately 14,400 B.t.u. per lb., a Hardgrove grindability index value of about 12, and approximately 1% ash, 7 to 10% sulphur, 4% combustible volatiles, and a fineness of 100% through a 30-mesh U.S. standard screen. Enormous quantities of such material are produced daily in such processes, creating a difficult disposal problem. In view of the fineness of the coke, transportation other than in closed vehicles is impracticable.

As shown, the coke is burned in a cyclone furnace 10 of the general type disclosed in U.S. Patent No. 2,357,301. The cyclone combustion chamber or furnace comprises a cylindrically shaped shell or barrel 11 of circular cross-section and arranged with its axis substantially horizontal. The barrel 11 of the furnace 10 is lined by refractory covered studded fluid cooled tubes 12 arranged side-by-side in opposite generally semi-circular loops having their ends opening to a lower fluid inlet header 13 and one of a pair of upper outlet headers 14, and 14'. The headers 13, 14 and 14' have their axes substantially parallel to the axis of the cyclone furnace. The outer or front end of the cyclone is formed by a frusto-conical end portion 15 formed by similar refractory covered fluid cooled tubes, and a central cylindrical inlet casing 16 concentric with the cyclone barrel. The opposite end of the furnace is provided with tube and refractory construction forming an outwardly flaring frusto-conical throat 17 which, with the barrel 11, defines an annular pocket 18 surrounding a gas outlet or throat passage 20. The tubes forming the wall 17 are extended to form an upright wall of a primary furnace 21 which, with a radiation chamber 22 separated therefrom by an inclined baffle 19, forms the lower portion of a steam generating and superheating unit of suitable type. The lower part of the pocket 18 is provided with a slag discharge port 23 opening into the primary furnace 21, so that any molten slag accumulating in the bottom of the furnace 10 will discharge across the floor 24, through a slag hole 25 therein, and thence into a slag tank 26.

As shown in Fig. 1, an oil burner nozzle 27 is inserted into the inlet casing 16, with the axis of the burner coinciding with the axis of the furnace 10. The burner nozzle 27 is constructed and arranged to project jets of oil toward the circumferential wall of the furnace 10. The inlet section 16 is provided with a tangential or involute connection to a fluid inlet duct 28 for the introduction of primary air and entrained solids, as herein-after described, and in addition with an inlet connection to a duct 30 for the controlled admission of tertiary combustion air to the furnace.

The barrel 11 of the furnace is formed with a horizontally elongated secondary air inlet section 31 for the tangential admission of a major portion of the combustion air along the length of the furnace. As shown in Fig. 2, the secondary air inlet section is provided with a damper 32 pivoted so that the tangentially entering air is directed along the circumferential wall of the furnace near the top thereof. The velocity of the entering secondary air may be controlled as desired, with changes in the volume of air delivered.

In accordance with the invention, a plurality of circumferentially elongated inlet ports 33 are positioned in a row disposed longitudinally of the furnace 10 at a position closely spaced circumferentially of the secondary air inlet section 31. As hereinafter described, the ports 33 are each supplied with a high velocity stream of air-borne particle-form coke which is admitted tangentially, whereby the coke particles mix with the secondary air stream in an impinging relationship thereto to form a swirling mixture of coke and secondary air. With the described introduction of air and coke, the mixture tends to swirl around the inner circumference of the furnace in a generally helical path towards the gas outlet 20. The throat 17 causes the gases to reverse direction and move inwardly of the furnace before the gases leave the furnace with an advantageous tendency to separate entrained solid matter from the gases before passing to the primary furnace chamber 21.

Referring to Fig. 1, the petroleum coke, which, as discharged from a fluidized coke process, is of minus 30 mesh fineness, is withdrawn from a coke storage bin 34 by a belt or pan type feeder 35 and regularly discharged through a rotating cup feeding and pressure sealing device 36. Conveniently, the feeder 35 is enclosed in an air-tight housing 37, with the rotary seal device 36 preventing flow of air or gases from the high pressure furnace 10 into the coke storage bin 34. From the rotary seal device, the coke discharges through a spout 38 into a transport pipe 40 where the coke is entrained in a suitable carrier medium, such as air, for delivery to the cyclone furnace 10.

The coke and carrier air is discharged through the transport pipe 40 and a flaring distributor 41 into a cylindrical manifold 42. The manifold receives the coke tangentially and discharges the coke through individual pipes 43, each connected with a corresponding port 33. The manifold 42 has a row of observation ports 44 in its side opposite the discharge pipes 43, the ports being closed by a removable cap member 45 having an observation window therein.

While low volatile low ash particle-form coke can be burned in a cyclone furnace of the character described with a supplementary fuel, such as oil or gas, it is advantageous to supply the cyclone with a material capable, with the furnace temperatures maintained, of forming a viscous sticky surface of molten material on the walls of the cyclone. Such a sticky surface will entrap the coarser particles of coke and retain them in the furnace in intimate scrubbing contact with the whirling stream of combustion air for a length of time sufficient to complete the combustion of the fuel. In the illustrated example of the invention, the petroleum coke has a low-ash content which is insufficient to form an adequate sticky surface of molten material on the wall of the cyclone. In accordance with the invention, a suitable slag-forming solid material which is molten under the high temperature conditions maintained in the furnace is supplied to the furnace for this purpose. This material may take the form of various low temperature clays and sand, or lime or other non-combustible refractory materials, having melting temperatures in the range of 2000 to 2400° F. Alternately, the slag-forming material may be a finely divided high volatile bituminous coal of average ash content supplied with primary combustion

air through the pipe 28 and inlet section 16. Under the latter condition, the supplementary fuel, such as oil, delivered by the burner 27 to develop and maintain coke ignition temperatures in the furnace 10 may or may not be used, depending upon the amount of bituminous coal supplied.

When a non-combustible refractory slag-forming material of the type indicated is supplied to the cyclone furnace separately from or as embodied in the auxiliary fuel, it is advantageous to recycle the slag-forming material for reuse in the furnace, so that the amount of make-up or fresh material will be kept to a minimum. For this purpose, the molten slag discharging through the slag hole 25 is arranged to fall into a pool of water 46, maintained in the tank 26, which causes the slag to be quenched and shattered into granular solid form. The granular slag is continuously or intermittently removed from the slag tank by a screw conveyor 47 and discharged into a pneumatic conveyor 48 for delivery to a slag storage hopper 50. The slag storage hopper is positioned above the cyclone 10 and is provided with a slag feeder 51 of the endless belt or apron type for the controlled discharge of the recycled slag through a rotary seal device 52 and a connecting spout 53 into the primary air duct 28 leading to the cylindrical inlet section 16 of the cyclone furnace.

In burning a low ash low volatile coke in the apparatus described, the combustion chamber is preferably brought up to the desired temperature by the combustion of oil fuel alone, and the non-combustible slag-forming material is added to the furnace to first form a viscous sticky film of slag on the refractory-covered walls of the furnace 10. The slagging material discharging from the spout 52 is entrained by the stream of air passing through the duct 28 and with the tangential delivery of the mixture of air entrained solids, the solids are centrifugally distributed to the walls of the combustion chamber. The air necessary for the combustion of the oil fuel can be supplied through the ducts 28 and 30, supplemented, as required, by air delivered through the inlet 31.

With a combustion chamber temperature sufficient to ignite the coke and to maintain the sticky slag surface on the walls of the furnace, the coke is delivered through the ports 33 to the furnace 10. With the combustion of coke, the quantity of oil delivered to the burner 27 may be gradually reduced until normal operating conditions are established, with a heat input ratio of oil to coke, for example, of 1 to 4. The burning swirling mass of coke, air and combustion products moves in a helical flow path towards the outlet 20. Any excess slag-forming material drains to the chamber bottom and discharges through the port 23 and slag hole 25 into the tank 26. Substantially all of the slag-forming material delivered to the furnace 10 is recovered in the slag tank 26 and can be recycled through the system. Make-up material is added to the bin 50 as required.

While the illustrated embodiment of the invention discloses the use of oil as a source of high volatile fuel, it will be understood a gaseous fuel can likewise be used to accomplish the desirable results of the present invention. When a gaseous fuel is used, the fuel is preferably introduced through burners positioned in the secondary air inlet 31 for mixing the combustion air within the combustion chamber 10. It will be also understood that a medium ash high volatile bituminous coal may be used to provide both a high volatile fuel source for burning the low volatile coke, and as a source of slag-forming material for the sticky surface of the combustion chamber.

While in accordance with the provisions of the statutes we have illustrated and described herein a preferred embodiment of the invention, those skilled in the art will understand that changes may be made in the method of operation and form of the apparatus disclosed without departing from the spirit of the invention covered by our claims, and that certain features of the invention may

sometimes be used to advantage without a corresponding use of other features.

What is claimed is:

1. The method of burning a low-ash content particle-form fuel at high rates of heat release which comprises continuously introducing a stream of combustion air at a high velocity substantially tangentially to the circumferential wall of a combustion chamber of circular cross-section, continuously introducing the particle-form fuel into said combustion chamber, causing the air and fuel so introduced to move axially of the combustion chamber through a helical path along the circumferential wall of the combustion chamber, and introducing a slag-forming particle-form solid material of low combustible content relative to said fuel from a separate source to said chamber while maintaining a combustion chamber temperature above the fusion temperature of said slag-forming solid material to form a viscous sticky surface on the circumferential wall of said combustion chamber in sufficient quantity whereby particles of said fuel tend to adhere to said sticky slag surface and to be burned by being scrubbed by the contacting combustion air.

2. The method of burning a low-ash content particle-form fuel at high rates of heat release which comprises continuously introducing a stream of combustion air at a high velocity substantially tangentially to the circumferential wall of a combustion chamber of circular cross-section, continuously introducing the particle-form fuel into said combustion chamber, causing the air and fuel so introduced to move axially of the combustion chamber through a helical path along the circumferential wall of the combustion chamber, introducing a separate slag-forming particle-form solid material to said chamber while maintaining a combustion chamber temperature above the fusion temperature of said slag-forming solid material to form a viscous sticky surface on the circumferential wall of said combustion chamber, whereby particles of said fuel tend to adhere to said sticky slag surface and to be burned by being scrubbed by the contacting combustion air, withdrawing the slag from said combustion chamber in a molten condition, quenching said molten slag to form particle-form solids, and recycling said particle-form solids to said combustion chamber.

3. The method of burning a low-ash and low-volatile content particle-form fuel at high rates of heat release which comprises continuously introducing a stream of combustion air at a high velocity substantially tangentially to the circumferential wall of a combustion chamber of circular cross-section, continuously introducing the particle-form fuel into said combustion chamber, causing the air and fuel so introduced to move axially of the combustion chamber through a helical path along the circumferential wall of the combustion chamber toward a gas discharge end thereof, introducing a slag-forming substantially non-combustible particle-form solid material from a separate source to the end of said chamber opposite to said gas discharge end, and separately introducing a high volatile fuel to said combustion chamber to maintain a combustion chamber temperature above the fusion temperature of said slag-forming substantially non-combustible solid material to form a viscous sticky surface on the circumferential wall of said combustion chamber, whereby particles of said fuel tend to adhere to said sticky slag surface and to be burned by being scrubbed by the contacting combustion air.

4. The method of burning a low-ash and low-volatile content particle-form fuel at high rates of heat release which comprises continuously introducing a stream of combustion air at a high velocity substantially tangentially to the circumferential wall of a combustion chamber of circular cross-section, continuously introducing the particle-form fuel into said combustion chamber, causing the air and fuel so introduced to move axially of the combustion chamber through a helical path along the circumferential wall of the combustion chamber toward

a gas discharge end thereof, introducing a separate slag-forming particle-form solid material to said chamber, introducing a high volatile fuel to said combustion chamber to maintain a combustion chamber temperature above the fusion temperature of said slag-forming solid material to form a viscous sticky surface on the circumferential wall of said combustion chamber, whereby particles of said fuel tend to adhere to said sticky slag surface and to be burned by being scrubbed by the contacting combustion air, withdrawing the slag in molten form from said combustion chamber, quenching said molten slag, and recycling said quenched slag to said combustion chamber.

5. The method of burning a low-ash and low-volatile content particle-form fuel at high rates of heat release which comprises continuously introducing a stream of combustion air at a high velocity substantially tangentially to the circumferential wall of a combustion chamber of circular cross-section, continuously introducing the particle-form fuel into said combustion chamber, causing the air and fuel so introduced to move axially of the combustion chamber through a helical path along the circumferential wall of the combustion chamber, and introducing a minor quantity of a separate air-borne high volatile and ash containing particle-form solid fuel separately to said chamber to maintain a combustion chamber temperature above the ignition temperature of said low-volatile particle-form solid fuel and above the fusion temperature of the ash of said separate high volatile fuel to form a viscous sticky surface on the circumferential wall of said combustion chamber, whereby combustible particles of both of said fuels tend to adhere to said sticky slag surface and to be burned by being scrubbed by the contacting combustion air.

35 6. The method of burning a low-ash and low-volatile content particle-form fuel at high rates of heat release which comprises continuously introducing a stream of combustion air at a high velocity substantially tangentially to the circumferential wall of a combustion chamber of circular cross-section, continuously introducing the particle-form fuel into said combustion chamber, causing the air and fuel so introduced to move axially of the combustion chamber through a helical path along the circumferential wall of the combustion chamber, introducing a separate air-borne high volatile ash containing particle-form solid fuel to said chamber to maintain a combustion chamber temperature above the ignition temperature of said low volatile particle form solid fuel and above the fusion temperature of said slag-forming solid material to form a viscous sticky surface on the circumferential wall of said combustion chamber, whereby particles of said fuels tend to adhere to said sticky slag surface and to be burned by being scrubbed by the contacting combustion air, withdrawing the slag in molten form from said combustion chamber, quenching said molten slag, and recycling at least a portion of said quenched slag to said combustion chamber with said air-borne high volatile ash containing solid fuel.

7. Apparatus for burning a low-ash content particle-form fuel at high rates of heat release comprising a combustion chamber of substantially circular cross-section defined by walls having an inner exposed refractory surface, a wall at one end of said combustion chamber including an inwardly projecting throat forming a gas outlet surface rounded by an annular pocket, means for introducing a major portion of the air required for combustion in a stream tangentially to said circumferential wall, means for introducing said low-ash particle-form fuel into said chamber, means for introducing a separate slag forming solid material into said combustion chamber to form a viscous sticky surface on the circumferential wall of said chamber, means for granulating said slag by quenching, and means for recycling said granulated slag-forming material to said combustion chamber.

75 8. Apparatus for burning a low-ash and low-volatile

content particle-form fuel comprising a combustion chamber of substantially circular cross-section defined by walls having an inner exposed refractory surface, a wall at one end of said combustion chamber including an inwardly projecting throat forming a gas outlet from said chamber surrounded by an annular pocket, means for introducing a major portion of the air required for combustion in a stream tangentially to said circumferential wall, means for introducing said low-ash particle-form fuel into said chamber, means for introducing a separate high volatile and slag-forming solid fuel into said combustion chamber to form a viscous sticky surface on the circumferential wall of said furnace, means for collecting said slag in molten form in and removing the molten slag

from the annular pocket surrounding said gas outlet, means for quenching the molten slag, and means for recycling at least some of said quenched slag to said combustion chamber.
